UNITED STATES PATENT OFFICE.

HARRY A. SMITH, JR., OF BUFFALO, NEW YORK.

ROTARY INTERNAL-COMBUSTION ENGINE.

1,300,036.

Specification of Letters Patent.

Patented Apr. 8, 1919.

Application filed January 30, 1918. Serial No. 214,514.

To all whom it may concern:

Be it known that I, HARRY A. SMITH, Jr., a citizen of United States, residing at Buffalo, in the county of Erie and State of 5 New York, have invented certain new and useful Improvements in Rotary Internal-Combustion Engines; and I do hereby declare the following to be a full, clear, and exact description of the invention, such as 10 will enable others skilled in the art to which it appertains to make and use the same.

This invention relates to internal combustion engines, and more particularly to a rotary engine or motor in which the gas is 15 compressed in stationary cylinders by cams which act upon compressing pinions, and in which the ignited or exploded gas exhausts against the pistons or blades carried by a rotor, for rotating the rotor.

20 Another object of this invention is to provide valves for controlling the exhaust ports of the cylinders which valves are operated by cams carried by the rotors so that the valves will be moved into an opening position when the piston heads are positioned 25 properly to be engaged by the exploding gas and further to provide a stationary cam structure engaging the piston heads or blades for forcing them inwardly after they 30 have traveled a predetermined distance of the circumference or rotation of the rotor to allow them to pass the other cylinders of the motor, and also to provide springs to project the piston heads or blades into an opposite 35 position when they reach proper positions with relation to the stationary compressing cylinders.

With the foregoing and other objects in view, this invention consists in such novel 40 features of construction, combination and arrangement of parts as will be hereinafter more fully described, illustrated in the accompanying drawings and claimed.

In describing the invention in detail, reference will be had to the accompanying 45 drawings wherein like characters designate like and corresponding parts throughout the several views and in which:

Figure 1 is vertical section through the 50 improved motor.

Fig. 2 is a vertical section taken on the line 2—2 of Fig. 1.

Fig. 3 is a fragmentary vertical section taken on the line 3—3 of Fig. 1.

Fig. 4 is a fragmentary section taken at 55 right angles to the section illustrated in Fig. 2, and illustrating the exhaust port controlling valve of the air compressing cylinder.

Fig. 5 is a side elevation of the improved motor.

Fig. 6 is a detail perspective view of one of the piston heads of the rotor.

Fig. 7 is a detail perspective view of the exhaust valve.

Fig. 8 is a section on the line 8—8 of 65 Fig. 3.

Referring more particularly to the drawings, 1 designates the supporting standards of the motor, which have suitable bearings 2 carried by their upper ends which bearings 70 in turn support the stationary shaft 3 of the motor.

The shaft 3 has a disk 4 keyed thereon as shown at 5 which disk forms one side of the motor casing and has a sleeve 6 formed 75 centrally thereof which encompasses the shaft 3 and forms a bearing for a rotatable section 7 of the motor.

The stationary disk 4 has a circular inwardly extending enlargement 8 formed upon its inner surface which enlargement is provided with a plurality of bores 9 extending inwardly from the circumference of the same, which bores form compressing cylinders and they have pistons 10 reciprocably mounted therein. Piston rods 11 are connected to the pistons 10 and they are slidably carried by spider structures 12 which are screwed in the upper end of the bores 9. The outer ends of the piston rods 11 are engaged by the inner surface of an internal cam 14 which is formed upon the rim 15 of the rotary section or portion 7 of the motor. Pins 16 extend through the piston rods 11 and springs 17 are coiled about the piston rods, engaging the pins 16 and the spiders 12 for normally forcing the piston upwardly and outwardly when the outer ends of the pistons reach the abrupt shoulder 18 of the internal cam structure 14. During the rotation of the internal cam structure 14, the piston heads are forced downwardly within the cylinder bores 9 by the portions 19 of the internal cam which are concentric with the center of the rotor and also of the stationary enlargement 8 and when the pistons reach the abrupt shoulders 18 the springs 17 act to draw the pistons upwardly and outwardly

within the bores 9, creating a suction through the inlets or intakes 20 of each bore 9, and consequently drawing charge of gas into the bores. Any ordinary type of intake valve as illustrated at 21 may be provided for controlling the intake of gas into the bores. The pistons 10 and consequently the piston rods 11 remain at their outermost positions for a relatively short time, or during the time in which the outer ends of the piston rods are engaged by the relatively short concentric portions 22 after which the pistons 10 are gradually forced inwardly for compressing the gas within the bores 9 by the inclined surfaces 23 of the internal cam structure while the gas is held compressed within the bores during the travel of the piston rods over the concentric portions 19 of the internal cam.

20 The compressed gas is fired within the lower ends of the bores 9 and it escapes out of the outlet openings 24 of each bore, impacting against the piston heads or blades 25 carried by the inwardly extending circular portion 33 of the rotor or rotary section 7 of the engine.

25 The exhaust ports or outlet openings 24 of the bores 9 are normally held closed by valve plates 26 which are slidably supported along side of the bores 9 and which are normally held in closing position by springs 27 which are mounted in bores 28 formed in the inwardly extending enlargement 8. The springs 27 engage pins 29 carried by the valve plates 26 and the tension of the springs may be regulated by adjustable screws 30 which are mounted in the outer edge of the bores 28.

30 Pins 31 are formed upon and depend from the lower edges of the valve plates 26 and they are engaged by cam surfaces 32 which are formed upon the periphery of the circular inwardly extending enlargement 33 of the rotary section 7, for moving the valve plates 26 into an open position at the time of the firing or exploding of the compressed gas within the bores 9 and at the proper time when the piston heads or blades 25 are positioned with relation to the bores 9, to receive the impact of the exploding gas.

35 The pistons 25 are slidably carried by the circular sections 33 of the rotor and they have springs 35 coiled about the rods 36 which are formed upon the piston heads. The springs 35 tend to force the piston heads or blades 35 outwardly, into an extended operative position and the pistons are forced inwardly within the openings 37, in which they ride, by the engagement of their outer ends with the inner cam surface of the stationary inwardly extending enlargement 8. The inner cam surface of the enlargement 8 is provided with a concave section 40 which terminates in abrupt shoulders and to the valve plates 26 so as to allow the springs 35

to force the pistons 25 outwardly to the limit of their outward movement at the time when the pistons reach the proper positions to receive the impact of the exploding gas. The concave surfaces 40 gradually incline inwardly toward the central axis of the motor, as shown at 41 so that by the time the piston has been forced from one of the cylinders to the next cylinder, it will also have been forced inwardly against the action of the springs 35, so that it will clear the cylinder next to the one from which the gas has exhausted against it, and after it has passed beneath the second cylinder and reached the abrupt shoulder of the concave portion 40 of the inner cam surface it will spring outwardly to receive the impact of the exploding gas from the second gas compressing piston throughout the entire operation of the motor.

40 In the construction of the engine or motor, there are twice as many piston blades as there are gas compressing cylinders, as will be noted by reference to Fig. 1 of the drawings, that permitting in an engine, embodying the number of cylinders and pistons illustrated in Fig. 1, 32 explosions to each revolution of the rotary element, since that each of the cylinders fires twice.

45 The rotary section 7 has an annular inwardly extending flange 46 attached to the free edge of the rim sections 15 thereof which flange extends into an annular recess 47 formed in the periphery of the stationary disk 4. Suitable ball bearings as indicated at 48 may be provided at the bearing surfaces between the flange 46 and the disk 4 if desired. The flange 46 is made in two sections as clearly shown in Fig. 1 of the drawings, which sections are connected by 105 right angularly extending flanges 49.

50 If it is so desired, ball bearings as indicated at 50 may be provided at the engaging bearing surfaces of the rotary and stationary part of the motor.

55 The gas exhausts, after it has been exploded, against the pistons 25, through suitable exhaust openings 55 which are formed near the point at which the movements of the extended positions of the pistons 25 terminate, as clearly shown in Fig. 1 of the drawings.

60 From the foregoing description taken in connection with the accompanying drawings the advantages of construction and the method of operation of the improved rotary internal combustion engines will be readily apparent to those skilled in the art to which this invention appertains and, while in the foregoing description, the principle of the operation of this invention has been described together with various features of construction, it is to be understood that certain minor features of construction, combination and arrangement of parts may be 130

altered to suit practical conditions provided such alterations are comprehended within the scope of what is claimed.

What is claimed is:

5. 1. In an internal combustion engine, a stator having a plurality of cylinder bores formed therein, gas compressing pistons in said bores, a rotor having inner and outer portions between which the stator is disposed, pistons carried by the inner portion of said rotor and means for causing gases exploded within the cylinder bores to act upon said pistons carried by the inner portion of the rotor so as to cause rotation of said rotor, 10 the outer portion of the rotor serving to operate said pistons.

2. In an internal combustion engine, a stator having a plurality of cylinder bores formed therein, gas compressing pistons in 20 said bores, a rotor having an inner portion arranged within the stator, and an outer portion encircling the stator, said outer portion being adapted to operate said gas compressing pistons, pistons slidably carried by 25 the inner portion of said rotor and arranged whereby the exploded gas passing from said cylinder bores will impinge against the slid- able pistons.

3. In an internal combustion engine, a 30 stator having a plurality of cylinder bores formed therein, gas compressing pistons in said bores, a rotor having an inner portion arranged within the stator and an outer portion encircling the stator, pistons slidably carried by the inner portion of said rotor and arranged whereby the exploded gas exhausting from said cylinder bores will impinge against the slid- able pistons, means 35 normally holding said slidable pistons in an extended operative position, cam surfaces carried by said stator for forcing said pistons inwardly into inoperative position, and a cam structure carried by said outer portion of the rotor to operate said gas compressing 40 pistons.

4. In an internal combustion engine, a stator having a plurality of cylinder bores formed therein, gas compressing pistons operative in said bores, a rotor having inner 50 and outer portions between which the stator is arranged, and an internal cam structure carried by said outer portion of the rotor and operable to actuate said gas compressing pistons to compress the gas in said bores, and 55 means carried by the inner portion of the rotor and adapted to be actuated by gases exploded within the cylinder bores for causing rotation of said rotor.

5. In an internal combustion engine, a

stator having a plurality of cylinder bores 60 formed therein, gas compressing pistons in said bores, valves for controlling the exhaust of gas from said bores, means normally holding said valves in closing positions, a rotor, 65 pistons slidably carried by said rotor and ar- ranged whereby exploded gas exhausting from said cylinder will impinge against the slid- able pistons, and cams carried by said rotor and engaging said exhaust controlling valves for permitting the exhaust of ex- 70 ploded gas from said bores.

6. In an internal combustion engine, a stator having a plurality of cylinder bores formed therein, gas compressing pistons in 75 said bores, valves for controlling the exhaust of gas from said bores, means normally holding said valves in closing positions, a rotor, pistons slidably carried by said rotor and ar- ranged whereby exploded gas exhausting from said cylinder will impinge against the 80 slid- able pistons, cams carried by said rotor and engaging said exhaust controlling valves for permitting the exhaust of exploded gas from said bores, an internal cam carried by 85 said rotor, piston rods attached to said gas compressing pistons and engaged by said internal cam whereby said cam will operate said pistons to compress gas in said bores.

7. In an internal combustion engine, a 90 stator having a plurality of cylinder bores formed therein, gas compressing pistons in said bores, piston rods connected to said pis- tons, a rotor, and an internal cam structure carried by said rotor and engaging said pis- ton rods to operate said pistons to compress 95 gas in said bores.

8. In an internal combustion engine, a stator having a plurality of cylinder bores formed therein, gas compressing pistons in 100 said bores, piston rods connected to said pis- tons, a rotor, an internal cam structure car- ried by said rotor and engaging said piston rods to operate said pistons to compress gas in said bores, valve plates to control the ex- haust of exploded gas from said cylinders, 105 means normally holding said plates in a clos- ing position, cams carried by said rotor for moving said valve plates into an opening position, and pistons carried by said rotor and arranged whereby exploded gas exhaust- 110 ing from said bores will impinge there- against.

In testimony whereof I affix my signature in presence of two witnesses.
